UNITED STATES PATENT OFFICE.

CHRISTIAN H. EISENBRANDT, OF BALTIMORE, MARYLAND.

RAILROAD-CAR COUPLING.

Specification of Letters Patent No. 24,109, dated May 24, 1859.

To all whom it may concern:

Be it known that I, CHRISTIAN H. EISENBRANDT, of the city of Baltimore, in the county of Baltimore and State of Maryland, 5 have invented and made certain new and useful Improvements in Railroad-Car Couplings; and I do hereby declare that the following, is a full, clear, and exact description of the same, reference being had to the 10 accompanying drawings, making a part of this specification, in which—

Figures 1 and 2, represent the truck or running part of the car, with the coupling devices attached thereto, and a fragment 15 taken out of the platform to show the devices as connected thereto. Figs. 3 and 4, represent the coupling devices detached from the car.

The nature of my improvements consists 20 in constructing a car coupling in such a manner, as that it is self coupling, and detachable when the cars are thrown off the track, and at the same time, acts as a brake or lock in connection with the wheels of the 25 car, thus performing the double office, at the same time of, self detaching and checking the cars, all of which will be more fully set forth hereinafter.

The construction of my improvements is 30 in the following manner. In Figs. 1 and 3 at a, a, a, a, a , are represented two metal plates of any desired and suitable shape, between which are inserted and securely attached, flat springs $a^2 a^2 a^3 a^3$ and indicated 35 also by the dotted lines $a^4 a^4$.

At $b, b-c, c-d, d-e, e$ are represented prong clasping grippers, the butt ends of which are jointed to the plates a, a, a, a , so as to open outwardly right and left, as indicated by the dotted formations b^2, b^2, b^2, b^2 , Fig. 3. One of the prong clasping grippers is formed with a catch place or notch e^2, c^2 , and the other one has a catch e^2 .

At f, f , is shown a small lever spring latch 45 with a pin g , and spring h, h , riveted on the back thereof. The pin g , is designed to fit into a perforation or hole in the lip part i , of the catch plate, c^2 , and catch e^2 .

At J, J , is represented a step plate, to be 50 attached by screws, or bolts, to the under side or bottom of the car truck as shown in Fig. 4. To this step plate J, J , is an upright bolt, or hitching pin, K, K , to which is attached at the upper end a chain or cord L, L, L, L , provided with a button or ring m, m . At n, n, n, n , Fig. 2, are represented

sliding rods, or bolts, attached by staples or otherwise, to the end of the car truck. These bolts have handles o, o , and hooking ends P, P .

The operation of my car coupling is as follows. When the cars are to be attached to each other, they are forced together as ordinarily done, when the bolt or hitching pin K, K , enters between the prongs c, c, e, e , causing them to open or expand, when the hitching pin or bolt K, K , after passing in between the clasping gripping parts b, b, d, d , presses forward, against the lever spring latch f, f , the pin g , thereby entering the lip part I , and holding the clasping grippers $b, b-d, d$, together securely so that the coupling can not become detached unless the cars are thrown off the track, and meet with accident.

In the movement of the cars forward, the couplings are together as shown in Figs. 1 and 2, but when the cars are thrown off the track, the hitching pin or bolt K, K , presses hard against the side of the clasping grippers $b, b-d, d$, when the latch lever f, f through the agency of the spring h, h , flies back thereby withdrawing the pin g , from the lip I , and causing the clasping grippers $b, b-d, d$, to expand or open, when the hitching pin or bolt K, K , becomes detached therefrom and the cars are disconnected.

A peculiar, and important additional feature of improvement pertaining to my coupling, is, that by the connecting of the button or ring m, m to the end r of the lever q, q, q , connecting with the brake of the car the cars can thereby be checked, or stopped by the detaching of the hitching pin K, K ; the checking power, being transmitted through the chain or cord L, L, L, L , when the drawing or pulling thereof presses down the end of the lever q, q, q , thus actuating the brake devices, which may be connected or combined with the coupling in the manner described and shown.

When it is desirable, to detach the cars by manual agency, the sliding bolts or rods n, n, n, o, o, P, P , are drawn outward laterally 105, when the prongs c', c', c', c' , are thereby opened and the hitching pin or bolt K, K , comes out.

The siding rods can be made sufficiently short so as to be within convenient and ready 110 reach of the operator in detaching the coupling. When the coupling is not to be de-

tached, the sliding bolts or rods are turned up, so as not to permit the ends p , p to be in the position as represented, in Fig. 2.

In Fig. 3, the dotted lines b^2 , b^2 , $\bar{b}^2$, indicate the position of the prongs c , c — e , e , when distended or open. The springs a^2 , a^3 — a^2 , a^3 cause the clasping grippers b — d , d , to react or close, immediately after the hitching pin K , K , passes in between them, as shown in Figs. 1, and 2.

The hitching pin K , K , is formed with a tenon at one end which fits into the step part J , J , securely, but is detachable therefrom when desired.

15 It will be observed, that my improvements perform the double office of detaching or uncoupling, and at the same time, locking or operating brakes of the car; thus acting automatically.

20 Having described the nature construction and operation of my improvements in car couplings, what I claim as new and desire

to secure by Letters Patent of the United States is as follows:

1. I claim the plates a , a , a , a ; with the 25 springs a^2 , a^3 — a^2 , a^3 ; the prong clasping grippers b , c , c^2 , d , e — e^2 , with the spring latch f , g , h , i , constructed, arranged, and operated substantially as set forth.

2. I also claim the hitching pin or bolt 30 K , K , provided with the chain and button, or ring L , L — M , M , when arranged, operated and used in combination with the clasping prong grippers b , c — c^2 — d , e — e^2 and brake lever g , g , g , r , substantially as 35 set forth and described.

3. I also claim the combination and arrangement of the sliding bolts n , o , p , with the prong clasping grippers b , c — c^2 , d , e , e^2 , substantially as set forth and described.

CHRISTIAN H. EISENBRANDT. [L. s.]
